UNITED STATES PATENT OFFICE.

WALTER H. LAWSON, OF RICHMOND, INDIANA.

BURIAL-CASKET.

No. 807,947.

Specification of Letters Patent.

Patented Dec. 19, 1905.

Application filed October 23, 1905. Serial No. 283,952.

To all whom it may concern:

Be it known that I, WALTER H. LAWSON, a citizen of the United States, and a resident of Richmond, in the county of Wayne and State 5 of Indiana, have invented new and useful Improvements in Burial-Caskets, of which the following is a complete specification, which when taken in connection with the accompanying drawings, forming a part thereof, is sufficiently clear and concise as to enable others skilled in the art to which it pertains to make and use the same.

My present invention relates to that class 15 of coffins in which a casket is changed to a couch or catafalque or conversely, as desired, and to provide new and novel means for accomplishing the transformation expeditiously.

The preferred manner of the construction 20 of my invention is shown most clearly in the accompanying drawings, in which—

Figure 1 shows an introspective plan view of the casket open as in Fig. 4. Fig. 2 is a longitudinal section of my casket as taken on the line U U of Fig. 1. Fig. 3 is a detail vertical section as taken on the line V V of Fig. 1. Fig. 4 is a vertical cross-section of my casket as taken on the line W W of Fig. 1 and showing the casket open. Fig. 5 is a vertical cross-section of my casket as taken on 25 the line X X of Fig. 1 and showing the casket closed. Fig. 6 is a detail perspective view of one of the operating-arms and its sheath or tube. Fig. 7 is a longitudinal sectional view taken through the part shown in Fig. 6. Fig. 30 8 is a detail perspective view of one of the hangers in which the operating-arms is engaged as shown in Fig. 4. Fig. 9 is a detail section as taken on the line Z Z of Figs. 5 and 11. Fig. 10 is a detail section as taken on the 35 line Y Y of Figs. 9 and 11, and Fig. 11 is a detail isometrical view of one of the guide-blocks and its accompanying rollers.

Similar reference characters denote and refer to like parts throughout the several views 40 of the drawings, and the arrows indicate the direction in which some of the views are taken.

In this construction the outer shell portion 45 of the casket is designated by the letters A, B, C, and D, said letters referring to the front, back, left-hand, and right-hand ends, respectively, while the letter H denotes the cover therefor, which cover is mounted by the two hinges E and F to the upper edge of the back B, as shown. It will be seen that 50 the shell formed as stated is minus a bottom therefor; but a relatively vertically movable

bottom I is provided, which is adapted to be moved up and down inside the shell, or in actual use the shell is moved up and down while the bottom remains stationary, and this 60 bottom I in reality becomes the base of the couch or inner section.

Rising vertically from the respective left and right hand ends of the bottom I and permanently connected thereto are the oval top 65 end members J and J'. Extending over the bottom I and supported some distance thereabove, as shown, is the couch-bottom K, and removably located between the members J and J' and rising from the rear edge of the 70 bottom K is the couch-back L. The members K, J, J', and L, in fact, comprise the couch proper, it being intended, of course, that the couch be properly upholstered and provided with a bed, (not shown,) which bed should 75 cover the entire top of the couch-bottom K and on which bed it is designed that the corpse shall be laid.

Located approximately on the center of the bottom I and below the bottom K is the vertically-disposed drum 1, having a pivot at both its lower and upper ends centrally thereof, the lower pivot being mounted in the socket-plate 2, as shown in Fig. 3, and the upper pivot being mounted centrally in the 80 apex of the spider 3, both the members 2 and 3 being secured to the bottom I, as shown in the drawings.

Secured in the face of the drum 1 and at different elevations are the cords 4, 5, 6, and 90 7, which I will now refer to. The outer ends of the respective cords 4 and 5 are secured to the inner ends of the respective coil-springs 9 and 10, said springs having their opposite ends permanently secured by the respective 95 staples or the like, (denoted by the numerals 11 and 12,) which staples are secured to and toward the left and right hand ends of the bottom I, substantially as shown. Said cords 4 and 5 are adapted to wind on the drum 1 in 100 opposite directions to each other, while the tension of the springs 9 and 10 is such as to normally keep said cords unwound. Located opposite and on a level with the cords 6 and 7 apertures are formed through the end members J and J', in which are mounted the respective spools or pulleys 13 and 14, over which the respective cords 6 and 7 may operate. The outer ends of said cords are permanently secured directly therebelow to inner surface and near the lower edges of the 105 respective left and right hand end members

C and D of the outer shell. The lengths of the cords 6 and 7 are such that when the shell is lowered, as in Fig. 4, the cords 6 and 7 are practically unwound from the drum 1, while at the same time the cords 4 and 5 will be wound thereon against the force of the springs 9 and 10. It is designed that the strength and the torsion of the springs 9 and 10 shall be such as to counterbalance the weight of the shell and its cover.

The movements of the shell vertically around the couch is guided and made practically frictionless by the following described means: Spaced apart and extending vertically parallel with each other and secured to the inner faces and near the inner ends of the end members C and D are the angle-iron guides, the guides M and N being located on the former and the guides M' and N' being located on the latter, whereby vertical guideways are formed between each pair, substantially as shown. Secured near the lower rear corners of the outer faces of the end members J and J' are the respective guide-blocks 15 and 16, one being shown in detail in Fig. 11, which blocks are alined midway of their respective pairs of guideways N M and N' M'. Each of said guide-blocks has two pairs of circular cavities formed in their faces whose arc cuts the edges of the blocks, and opposite thereto each two have one point in common centrally of the blocks, as shown. Disposed revolubly in each of said cavities is a roller-disk, as the upper disks 17 and 18 and the lower disks 19 and 20 in the block 15 and the upper disks 21 and 22 and the lower disks 23 and 24 in the block 16, as shown. Each of said disks projects somewhat beyond the edge of the blocks, and opposite thereto the peripheries of each pair of disks are juxtaposed with each other, all substantially as shown in Fig. 11. The antipodal peripheries of each pair of said disks are adapted to contact with the inward face of the respective guides to form rollerbearings, substantially as shown in Figs. 4 and 9. It will now be notably apparent that if the casket be arranged on supports—for instance, the pedestals 98 and 99—contacting only with the under side of the bottom I, as shown in Figs. 2, 4, and 5, the shell of the casket may be freely moved up and down, being practically frictionlessly mounted and counterbalanced by the arrangements above set forth.

The means for actuating the shell vertically by the operation of opening and closing the cover of the casket: As afore intimated, the upper edges of the end members J and J' are oval, formed in the segment of a circle, the exact curvature being accurately predetermined according to the size of the casket and the curve described by the cover and the movements of the shell. Formed in the center of the upper edge of said end members J and J' is a half-round channel in which is partially embedded the respective tubes 25 and 26, each

having an ear at each end thereof, whereby it may be secured by screws or otherwise. The numerals 27 and 28 each represents an arm operative back and forth telescopically in the respective tubes 25 and 26, substantially as shown. Extending at right angles from the outer ends of the respective arms are the coupling-hooks 29 and 30. Formed longitudinally in the tubes 25 and 26, in their upper faces, is a slot, (shown in Fig. 6,) extending from their rear ends to substantially half their lengths, through which the shanks of the respective hook members 29 and 30 may glide back and forth. Secured on the inside of the cover H, opposite said hooks 29 and 30, are the respective hangers 31 and 32, each having an eye in its projecting end which engages the respective hooks 29 and 30, as shown in Figs. 4 and 5. Extending down at right angles from the inner end of the arms 27 and 28 is a pin-stop (only one of which can be seen in the drawings and that being indicated by the numeral 8 in Fig. 7) which operates in slots therefor formed in the under side of the tubes and of a length as only to allow the arms 27 and 28 to have a limited movement rearward to bring the cover to a vertical position, as shown in Figs. 1 and 4.

From the above it will be noticed that when the cover is down, as in Fig. 5, the hooks 29 and 30 are in the forward end of the upper slot of the tubes and the pin-stops are in the forward ends of the lower slots of the tubes, and, conversely, when the lid is raised, as in Fig. 4, the said hooks glide through and beyond the upper slots, while the pin-stops glide to the rear ends of the lower slots and prevent the cover from moving farther rearward. It will also be seen that as the cover is moved to its opened and closed positions the arms 27 and 28 will move telescopically in and out in their respective tubes 25 and 26, whereby in order to adjust their movements to the curvature of the tubes, which are relatively stationary, the shell will of necessity be moved up and down within the limits indicated in Figs. 4 and 5, very little effort being required to actuate said movements, the mechanism being so nicely balanced that the lid will remain at any angle within its radius at which it may be left.

In order that the couch portion may be supported inside the shell when the casket is lifted from the pedestals, I provide a plurality of detents, as the pins indicated by the letter P in various parts of the drawings, which pins extend inward from the lower edge of the inner face of the shell, as shown, to engage the under side of the bottom I; but in order that the under side of the bottom I may come flush with the lower edge of the shell a slot (denoted by the letter S) is cut in the under side of the lower edges of the bottom I, one for each pin to enter, all substantially as shown in the drawings.

The shell is prevented from dropping downward farther than that shown in Fig. 4 by two pairs of stops, one pair being located at each end of the casket, the stops 35 and 36 being secured horizontally on the outer faces and near the lower forward corners of the respective end members J and J' of the couch and the stops 37 and 38 being secured horizontally on the inner faces and near the upper forward corners of the respective end members D and C of the shell. By this arrangement it is apparent that as the shell is lowered the faces of the stops 37 and 38 will impinge the opposing faces of the stops 35 and 36, and thus prevent further movement downward of the shell.

From the above description, taken in connection with the accompanying drawings, it is believed that my invention, its operation, and its advantages will be fully understood without further insistence.

Having now fully shown and described my invention and the best manner for its construction to me known at this time, what I claim, and desire to secure by Letters Patent of the United States, is—

1. A burial-casket having in combination, an outer shell, a cover hinged to the shell, a relatively stationary couch located within the shell, a vertically-disposed drum carried centrally of the base of the couch, a pair of oppositely-disposed springs secured longitudinally in the base, a cord or the like extending from the free ends of the said springs and secured to the face of the drum to wind thereon in opposite directions, a pair of cords or the like secured to the face of the drum to wind thereon in opposite directions and having their ends extending out to the inner faces of their respective ends of the shell and then extending downward and being secured near the lower edges of the ends of the shell, means for guiding the shell vertically and frictionlessly over the couch, and means for moving the shell vertically by opening and closing the cover, all substantially as shown and described.

2. A burial-casket having in combination, an outer shell, a cover hinged to the shell, a relatively stationary couch located within the shell, a pair of guides spaced apart and secured to the inner faces and near the rear of the ends of the shell and at either end thereof, guide-blocks secured to the ends of the

couch opposite and between each pair of guides, two pairs of disks revoluble loosely in each of said guide-blocks and adapted to travel on the opposing faces of the guides, means for counterbalancing the shell in connection with the couch, and means for operating the shell vertically by opening and closing the cover, all substantially as shown and described.

3. A burial-casket having in combination, an outer shell, a cover hinged to the shell, a relatively stationary couch located within the shell, means for guiding the shell vertically, means for counterbalancing the shell in connection with the couch, a tube secured in the upper edge of the upwardly-projecting ends of the couch, a hanger secured inside the cover and alined with its respective tube, an arm telescopically mounted in each of said tubes with their outer ends pivoted in the respective hangers on the cover whereby as the cover is opened and closed the shell and the lid will be lowered and raised respectively, all substantially as shown and described.

4. A burial-casket having a movable outer shell, a cover hinged to the shell, a couch located within the shell, the counterbalancing means for connecting interiorly the shell and the couch, guides secured on the inner faces of the ends of the shell, guide-blocks secured to the outer ends of the couch and carrying roller-disks therein, the roller-disks mounted in said guide-blocks and adapted to travel in guideways formed by said guides, means for automatically actuating the vertical movements of the shell by the operation of opening and closing the lid, said means consisting of curved arms attached to the lid and operative in tubes secured on the upper segmental edges of the ends of the couch, the tubes in which said arms operate with means for their attachment to the couch, and means for supporting the couch by and entirely within the shell when the casket is lifted from its supports, all substantially as shown and described.

100

In testimony whereof I have hereunto signed my name in the presence of two subscribing witnesses.
